UNITED STATES PATENT OFFICE.

GRENVILLE MELLEN, OF EAST ORANGE, NEW JERSEY, ASSIGNOR TO CONTINUOUS
CASTING CORPORATION, OF RICHMOND, VIRGINIA, A CORPORATION OF VIR-
GINIA.

CASTING-POT.

1,139,886.

Specification of Letters Patent. Patented May 18, 1915.

Original application filed May 16, 1914, Serial No. 839,045. Divided and this application filed June 29, 1914. Serial No. 848,013.

To all whom it may concern:

Be it known that I, GRENVILLE MELLEN, a citizen of the United States, residing at East Orange, in the county of Essex, and State of New Jersey, have invented certain new and useful Improvements in Casting-Pots, of which the following is a specification.

My invention relates to a casting-pot provided with means for delivering molten metal to a continuous casting machine, such as that shown in my application Serial No. 839,045, filed May 16, 1914, of which this application is a division.

In the operation of this continuous casting machine, it is important that the molten metal shall be delivered to the moving molds at a definite, controllable and maintained rate, and it is the purpose of this invention to provide means for so delivering the metal.

This object I attain by providing the pot which contains the main body of molten metal with an extension or chamber within which there is maintained a quantity of molten metal always at substantially the same level, the metal flowing from this extension or chamber thus being maintained under a practically constant hydraulic head.

My invention further relates to the means for automatically maintaining the level of the molten metal and to other features which will more specifically appear from the specification and claims.

In the accompanying drawings—Figure 1 is a sectional elevation of the casting-pot and the end portion of the casting machine; Fig. 2 is an elevation of the casting-pot, on a plane at right angles to the plane of Fig. 1, the parts of the casting machine being omitted; Fig. 3 is a sectional elevation of the casting-pot extension, on a larger scale; and Fig. 4 is a view, partly in section and partly in perspective, showing the ball and socket connection between the outlet and delivery tube.

Referring to Figs. 1 and 2 of the drawings, 1 is a suitable bed-plate, upon which is supported a movable furnace 2, mounted upon wheels 3, 4, running on tracks 5, 6. The furnace 2, which may be moved to and from the molds by the hand-wheel 7, has a fire-box 8, lined with suitable fire-brick 9, and a grate 10, below which is the ash-pit 11. The furnace structure supports a jacket or casing 12, covered by a dished cover 13,

perforated at 14. Within the jacket 12 and supported upon adjustable screws 16, is a casting-pot 15, into which is poured the molten metal to be subsequently cast. The cover 13 serves as a funnel for molten metal; and as a shelf for solid low-melting metals, such as lead, etc., the heat from the furnace 2 generally being sufficient to melt and maintain melted such low-melting metals. The products of combustion from the furnace 2 pass through the annular space 17 between the jacket and casting-pot, under the cover 13 and through the opening 14 to any suitable draft-flue, not shown; the shape of the cover 13 serving to deflect heat down into the casting-pot and onto the surface of the molten metal, and to maintain a deoxidizing atmosphere in contact therewith. 15' is a shield to prevent splashing of molten metal over the edges of pot 15, when metal is poured into the pot.

Connected to the bottom of the casting-pot 15 is an extension 18 covered by the disk valve-seat 19, the extension having an outlet tube 20, arranged to be closed by a valve 21. Within the extension 18 is a suitable guide 22, through which passes the rod 23 carrying an adjustable float 24 and valve-plug 25, which latter co-operates with the valve-seat in the disk 19 to control the supply of molten metal passing into the extension 18. The guide 22 is so constructed as to act as a guard for preventing the molten metal from striking directly on the float 24. At its upper end, the rod 23 is supported by knife-edges 26 on the balance-arm 27, the balance-arm in its turn being supported on knife-edges 28, and carrying the adjustable counterpoise 29. The float 24 may be of iron or any suitable material and may be either solid or hollow. The float 24 and counterpoise 29 are each adjustable, and are adjusted to automatically supply metal from the casting-pot 15 to the extension 18 as fast as it is used, keeping a predetermined quantity of metal 31 in the extension 18 to operate the float, and thereby maintain a uniform "head" or pressure of metal in the extension. The casting-pot 15 is heated by the furnace 2, which is blown by blower 30, preferably electrically driven. The furnace is automatically centered horizontally with respect to the molding-machine by the wheels 3, 3, having V-shaped grooves in their pe-

riperies and rail 5, shown in Figs. 2 and 3. The casting-pot 15 is vertically centered with respect to the molding-machine by the adjusting screws 16 which pass through the 5 casing 12, as shown, and permit an elevation or lowering of the casting-pot 15 and its outlet 20 to allow for differences of expansion and contraction between the furnace and the molding-machine.

10 As seen in Figs. 1 and 4, the extremity of outlet 20 contains a cavity or socket 33, closed by a bushing 34; the lower side of bushing and outlet being slotted, as at 36, as hereafter described. Passing through the 15 hole in the bushing is a feeding-tube 37, having an enlarged ball-shaped end 38, forming a ball-and-socket joint with the cavity 33 in the outlet 20. At its other end the feeding-tube 37 is shaped to engage the inner 20 walls of the chamber formed within the series of coöperating traveling molds consisting of mold-sections 46, preferably loosely linked together, and each having a segment of a mold on its working-face, the 25 working-faces of the coöperating molds uniting to form a complete mold.

Should it be desired to drain the casting-pot of its contents, the furnace is rolled back on the tracks, drawing the feeding-tube 37 30 with it; as the latter leaves the molding-machine, the feed-tube falls down below horizontal, in the slot 36, as shown in dotted lines in Fig. 4, the metal in the casting-pot or extension 18 draining through the feeding-tube into any suitable receptacle. The casting-pot 15 and extension 18 may also be drained by opening the plug 18' at the bottom of the extension, in the event of an 35 accident to the outlet 20. The mold-sections are propelled or pushed by the sprocket wheels 51, 52, the teeth of which press against rollers secured to each mold-section. The sprocket wheels are mounted on shafts 53, 54, driven by suitable mechanism.

40 The operation of the device will be apparent from the above description. The molten metal, kept fluid by heat from the furnace 2, when the valve 25 is opened, flows into the extension 18 and rises therein to the desired level. This point is determined by the adjustment of the float 24 and weight 29 to the proper positions on rod 23 and arm 27. Assuming that molten metal has been permitted to enter the extension and rise therein 45 until the valve 25 has been closed by the rising of the float 24, as soon as metal is permitted to flow through the outlet tube 20, the level of the metal in the extension lowers and the float sinks, thereby partially opening the valve to admit additional metal until the desired level of metal is attained. This level is thereafter automatically maintained because the buoyancy of the float, partially 50 balanced by the weight 29, causes the valve 55 to narrow the entrance opening as the level

rises and to enlarge this opening as the level falls. This maintained head of molten metal in the extension causes the metal to flow from the outlet tube 20, at a uniform rate, thereby insuring delivery of a constant 70 supply of molten metal to the casting machine.

I claim:—

1. The combination of a casting-pot, an extension thereto and in closed communication therewith, a valve closing the entrance to said extension, an adjustable float in said extension, said valve opened and closed by the movement of said float. 75

2. The combination of a casting-pot, an extension thereto and in closed communication therewith, a valve closing the entrance to the extension, a float in said extension connected to said valve, said valve opened and closed by the movement of said float. 80

3. The combination of a casting-pot, an extension thereto and in closed communication therewith, means to supply molten metal from said casting-pot to said extension, and means to automatically maintain a predetermined quantity of molten metal in said extension. 85 90

4. The combination of a casting-pot, an extension thereto, a controlling valve therefor, a valve-plug, a float, a supporting-rod, counterpoise means on said supporting-rod, said valve-plug and float supported by said supporting-rod and arranged to coöperate to open and close said valve. 95

5. A casting-pot having a delivery tube 100 for molten metal and a feed conduit universally joined to said delivery tube.

6. A casting-pot having a delivery tube for molten metal and a feed conduit universally joined to said delivery tube, and 105 means permitting said feed conduit to drop and drain said casting-pot.

7. The combination with a casting-pot having a downward extension, of a casing surrounding said pot and extension, a heating device in the lower portion of said casing, a feed conduit extending through the wall of the casing and connected to the extension, and means for adjustably supporting the casting-pot within the casing. 110 115

8. The combination with a casting-pot having a downward extension in closed communication therewith, an annular valve seat at the entrance to said extension, a valve plug for engaging said valve seat, a rod on which said plug is carried, a float supported on said rod, and a guide for said rod within said extension. 120

9. The combination with a casting-pot, of a casing surrounding the same, said casing having a downwardly and inwardly inclined centrally perforated cover extending over said pot. 125

10. The combination with a casting-pot, of a casing surrounding the same, said cas- 130

ing having a downwardly and inwardly inclined cover extending over said pot, said pot having an inwardly extending shield secured to and extending around its upper

5 edge.

11. A casting-pot having a downwardly projecting extension for receiving molten metal, a valve for admitting molten metal from said pot to said extension, and an inwardly extending shield secured to the upper edges of the pot.

12. A casting-pot having an outlet tube, said tube having formed near its outer end a

spherical socket, a bushing screwed into said tube and having a slot in its lower portion, 15 a feeding tube of less width than said slot, having a spherical end secured between the end of said bushing and the socket in the outlet tube.

In testimony whereof I affix my signature 20 in presence of witnesses.

GRENVILLE MELLEN.
